CLAIM

The ornamental design for a machine tool, substantially as shown and described.

DESCRIPTION

FIG. 1 is a perspective view of a machine tool showing my design.

FIG. 2 is a front view of the machine tool of FIG. 1.

FIG. 3 is a back view of the machine tool of FIG. 1.

FIG. 4 is a right side view of the machine tool of FIG. 1.

FIG. 5 is a left side view of the machine tool of FIG. 1.

FIG. 6 is a top view of the machine tool of FIG. 1; and,

FIG. 7 is a bottom view of the machine tool of FIG. 1.

The broken lines illustrate features that form no part of the claimed design.

1 Claim, 7 Drawing Sheets(56)
